(57) CLAIM

The ornamental design for a metal food container, as shown and described.

DESCRIPTION

FIG. 1 is a perspective view of the metal food container; FIG. 2 is a front elevation view of the metal food container, and the rear, right, and left elevation views being the same as the front elevation view;

FIG. 3 is a top plan view of the metal food container; FIG. 4 is a bottom plan view of the metal food container; and,

FIG. 5 is a sectional view of the metal food container taken along line 5-5 of FIG. 3.

The broken lines depict portions of the metal food container in which the design is embodied that are not considered part of the claimed design. The dot-dash broken line defines the bounds of the claimed design and forms no part thereof.
